UNITED STATES PATENT OFFICE.

JOHN J. OSBORNE, OF NEW YORK, N. Y.

DESIGN FOR A DOLL.

Application filed November 28, 1924. Serial No. 11,523. Term of patent 14 years.

To all whom it may concern:

Be it known that I, JOHN J. OSBORNE, a citizen of the United States, residing at 300 West 49th Street, New York city, New York, have invented a new, original, and ornamental Design for Dolls, of which the following is a specification, reference being had to the accompanying drawing, forming part thereof.

In the drawing:

I claim:

The ornamental design for doll, as shown.

JOHN J. OSBORNE.
